US00D998644S

(12) **United States Design Patent** (10) **Patent No.:** **US D998,644 S**
Bachman et al. (45) **Date of Patent:** **** Sep. 12, 2023**

(54) **ELECTRONIC DEVICE WITH GRAPHICAL USER INTERFACE**

(71) Applicant: **Apple Inc.**, Cupertino, CA (US)

(72) Inventors: **William Martin Bachman**, San Jose, CA (US); **Monika E. Gromek**, Oakland, CA (US); **Joseph Andrew Magnani**, San Francisco, CA (US)

(73) Assignee: **Apple Inc.**, Cupertino, CA (US)

(**) Term: **15 Years**

(21) Appl. No.: **29/853,745**

(22) Filed: **Sep. 19, 2022**

Related U.S. Application Data

(63) Continuation of application No. 29/716,262, filed on Dec. 9, 2019, now Pat. No. Des. 964,402, which is a continuation of application No. 29/649,899, filed on Jun. 3, 2018, now Pat. No. Des. 869,491.

(57) **CLAIM**

The ornamental design for an electronic device with graphical user interface, as shown and described.

DESCRIPTION

FIG. 1 is a front view of an electronic device with graphical user interface showing the claimed design; and, FIG. 2 is a front view of an alternate electronic device showing the graphical user interface of FIG. 1 applied thereto.

The outer dashed broken lines in the figures show an electronic device having a display screen, or an alternate electronic device having a display screen, and form no part of the claimed design.

The other dashed broken lines in the figures show portions of the graphical user interface that form no part of the claimed design.

The dot-dash broken lines in the figures and the areas within the dot-dash broken lines show portions of the graphical user interface that form no part of the claimed design.

The dot-dot-dash broken lines in the figures and the areas between the dot-dot-dash broken lines and the outer dashed broken lines show portions of the graphical user interface that form no part of the claimed design.

1 Claim, 2 Drawing Sheets
